UNITED STATES PATENT OFFICE.

EDSON E. GOODRICH, OF WATERVILLE, MAINE.

FOLDING UMBRELLA.

No. 866,015.

Specification of Letters Patent.

Patented Sept. 17, 1907.

Application filed May 19, 1906. Serial No. 317,846.

To all whom it may concern:

Be it known that I, EDSON E. GOODRICH, a citizen of the United States, residing at Waterville, in the county of Kennebec and State of Maine, have invented 5 certain new and useful Improvements in Folding Umbrellas, of which the following is a specification.

The object of my said invention is to provide an umbrella frame which is adapted to fold, in order that the umbrella may be conveniently folded and packed 10 in a trunk or satchel when desired, all as will be hereinafter more fully described and claimed.

Referring to the accompanying drawings which are made a part hereof and on which similar reference characters indicate similar parts, Figure 1 is a view 15 of an umbrella frame in elevation with the parts in the position they occupy when the umbrella is ready for use, the ribs being only partially elevated and only two of said ribs being shown, in order that the illustration may be more clear, Fig. 2 is a view of said 20 frame showing the stem and ribs in folded position and the handle released and ready to be folded, Fig. 3 a detail view illustrating the joint in the ribs more clearly, Fig. 4 a cross-section through one of said ribs on the dotted line 4—4, Fig. 5 a detail view on an 25 enlarged scale of the slide, and Fig. 6 is a view of the frame and handle folded.

It will be understood that the cover is attached to the frame in the same manner as to any ordinary umbrella frame and being of flexible material does not in 30 any manner interfere with the operation of the parts. It is omitted from the drawings in order that the framework, to which the invention relates, may be more clearly illustrated.

In said drawings the portions marked A, A' and A² 35 represent the different parts of the stem and handle, B, B' the two parts of the ribs and C the braces.

The stem comprises the part A which is preferably a metal tube of suitable size, similar to the upper end of an ordinary umbrella stick, and internally screw-threaded at its lower end. The part A' may be tubular or solid, as preferred, adapted to telescope within the part A and provided with a screw-threaded upper end a which is adapted to engage with the internally screw-threaded part at the lower end of the part A. 40 The handle A² may be of any desired form and is formed with a socket with an internal screw-threaded portion a⁵ at the lower end of said socket therein, with which the screw-threaded part a' is adapted to engage. Said part a' is hinged to a short section a² which in 45 turn is hinged to the lower end of the part A', thus forming a double hinge and enabling the handle to be folded back on the outside of the cover, which may surround the ribs when folded, in the position shown in Fig. 6.

50 The ribs are formed in two sections B B' hinged together on pivots b which pass through the two parts.

The part B is preferably solid and thinner than the part B', which is formed U-shaped in cross-section as shown in Fig. 4, and adapted to receive said part B between its sides. The end of the part B' extends upwardly 60 for a distance beyond said pivot so that while the part B may fold upwardly as shown in Figs. 2 and 6, it is held from folding inwardly on the pivot when extended. By this construction the ribs when extended are not only held rigid but the two parts are in line with 65 each other, making a practically continuous rib without perceptible off-set or joint.

The braces C are pivotally attached to clips b' mounted on each of the parts B a short distance above the pivots b and at their lower ends are pivotally connected to the top of a slide C' in the usual manner. A spring pawl C² is mounted on a pivot c on one side of said slide, its upper end being adapted to project through an adjacent perforation therein and engage with a perforation a³ in the part A of the stem and hold the 70 ribs in extended position, and engage under a catch c⁴ on the part A' of said stem to hold the frame in closed position when it is not to be folded. A spring c' serves to hold said pawl to engage said catches when slid to the proper positions. 80

In operation, the umbrella being in position for use, and it being desired to fold the same, the slide C' is disengaged from the catch or perforation a³ and the ribs brought to about the position shown in Fig. 1, when the umbrella is turned up side down allowing the ribs to 85 fall back to the position shown in Fig. 2, the cover falling between the two parts of said ribs. The slide C' is then pushed up to the top of part A of the stem, as also shown in Fig. 2, which folds the braces C under said ribs. The handle A² is then turned to disengage its 90 threaded portion a⁵ from the screw-threaded end of the part a' which is jointed to the frame. When said parts are disengaged the handle will fall to the position shown in Fig. 2. The part A' is then screwed inwardly until the threaded portion is disengaged from the internally 95 threaded lower end of the part A, when said part A' will telescope within said part A, as shown in Fig. 2. The handle A² is then folded back to the position shown in Fig. 6 and the whole may be then incased in a suitable cover, when it is ready for packing. It being desired to put the umbrella in condition for use when folded in the position shown in Fig. 6, it is done by holding the umbrella in a vertical position with handle down, allowing said handle A² to fall down in the position shown in Fig. 2, when it is slid upwardly over the 100 hinge parts a' and a² until the screw-threaded end of part a' engages with the screw-threaded socket a⁵ in the handle, when said handle is turned until the two parts are firmly engaged, the upper end of the handle thus covering the joints of the hinge and holding the parts 105 rigid. The part A' is then turned backwardly until the screw-threaded section at its top end is firmly engaged 110

in the internally screw-threaded portions at the lower end of part A when the handle and stem of the umbrella are to all intents and purposes the same as any stick and handle of an ordinary umbrella. The slide C' is then 5 slid down the stem to about the position shown in Fig. 1 and parts B' of the ribs are allowed to fall down in the position shown in said figure. Said ribs are then extended by sliding the slide C' upwardly until the latch c² engages the catch a³ in part A. The braces bear 10 against the part B beyond the joints b and serve to tighten the cover and hold said ribs straight and approximately rigid, the strain of the cover being on a line inside the pivot in each one.

By this construction, a folding umbrella is provided 15 wherein, when in use, all of the joints and devices for enabling it to be folded are concealed and to all intents and purposes only an ordinary umbrella construction is shown.

Having thus fully described my said invention, what 20 I claim as new and desire to secure by Letters Patent, is:—

1. In a folding umbrella, the combination, of the three part stem and handle comprising the parts A and A' adapted to telescope and connect by screw-threads and 25 the handle A² adapted to telescope on the lower end of the part A' and be connected thereto by screw-threads, the jointed ribs composed of the parts B and B', and the braces C connected with the slide C' and said ribs above the joints therein, substantially as set forth.
- 30 2. A folding umbrella comprising a stem having a hollow upper section with an internally screw-threaded lower end, another section adapted to telescope therein with an external screw-threaded upper end to engage the threads of said first section, a handle mounted on the 35 lower end of said second section by means of a jointed section with a screw-threaded end adapted to engage with a screw-threaded portion in the bottom of a socket in said handle, said handle being adapted to telescope over and cover the joints in said section, and the ribs and braces, 40 substantially as set forth.
3. A folding umbrella comprising a stem composed of

telescopic sections, means for holding them in extended position, the lower end of the telescoping section provided with a hinged portion, a handle for engagement with such hinged portion and adapted to slide over the hinge and hold the parts rigid, the folding ribs, the braces, and the slide, substantially as set forth. 45

4. A folding umbrella comprising a stem composed of the telescopic sections A and A', means for holding said sections in extended position, a hinge composed of a parts a' and a² pivoted to the lower end of section A', said part a' being formed screw-threaded, and a handle formed with a socket adapted to slide over said hinge to hold it rigid and formed with a screw-threaded portion at the bottom of its socket for engagement with the screw-threaded part a' of the hinge, whereby the parts may be held in line, the folding ribs, the braces, and the slide, substantially as set forth. 50

5. In a folding umbrella, the combination, with the stem, of a handle mounted on its lower end by means of a section jointed both to the lower end of the stem, and to a screw-threaded section adapted to engage with a screw-threaded socket in said handle, whereby a double hinge joint is provided to enable said handle to be folded outside the cover, substantially as set forth. 60

6. A folding umbrella comprising a stem made in sections adapted to fold and telescope, ribs formed in two parts, one of said parts being U-shaped in cross section and adapted to embrace the end of the other part, said other part mounted between the sides of said U-shaped part on a pivot secured in said sides, said part being formed with an extension extending beyond said pivot and adapted to bear against the edge of said U-shaped part and hold said joint from bending in one direction, whereby the rib when extended is held rigid and its parts in line 75 with each other, the braces connected at one end with said ribs at a point above said pivots and at the other end to a slide on the stem, and said slide, substantially as set forth.

In witness whereof, I, have hereunto set my hand and 80 seal at Augusta Georgia this 14th day of May, A. D. nineteen hundred and six.

EDSON E. GOODRICH. [L. S.]
